UNITED STATES PATENT OFFICE.

JACOB J. SMITH, OF DENVER, COLORADO, ASSIGNOR OF FIFTY-ONE ONE-HUNDREDTHS TO ARTHUR R. WILFLEY, OF DENVER, COLORADO.

SLIME-SAVING APPARATUS.

SPECIFICATION forming part of Letters Patent No. 761,615, dated May 31, 1904.

Application filed December 15, 1902. Serial No. 135,324. (No model.)

To all whom it may concern:

Be it known that I, JACOB J. SMITH, a citizen of the United States of America, residing in the city and county of Denver and State of Colorado, have invented certain new and useful Improvements in Slime-Saving Apparatus; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to improvements in slime-saving tables or apparatus, my object being to provide means for saving the exceedingly fine mineral values usually termed "slimes" which are held in suspension by the water and ordinarily lost in the tailings. This apparatus is more especially intended for use in connection with other concentrates, the arrangement being such that the tailings or a portion of them are discharged upon my improved table, which saves the values contained therein; and to these ends the invention consists of the features, arrangements, and combinations hereinafter described and claimed, all of which will be fully understood by reference to the accompanying drawings, in which 30 is illustrated an embodiment thereof.

In the drawings, Figure 1 is a top or plan view of my improved apparatus. Fig. 2 is a side elevation of the same. Fig. 3 is a longitudinal section taken on the line 3 3, Fig. 1. Fig. 4 is a similar section taken on the line 4 4, Fig. 1. Fig. 5 is a section taken on the line 5 5, Fig. 1, shown on a larger scale. Fig. 6 is a section taken on the line 6 6, Fig. 1, viewed in the direction of the arrow, the parts being shown on a larger scale. Fig. 7 is a section taken through one of the feed-gates. This section may be designated as taken on the line 7 7, Fig. 5.

The same reference characters indicate the same parts in all the views.

Let the numeral 5 designate the table, which, as shown in the drawings, is provided with a central longitudinal partition 6, having a slot 6^a, which extends from the foot or left-hand

extremity of the table, referring to Figs. 1 and 2, a short distance toward the head or opposite extremity thereof. The outer edge of the table is surrounded by a vertical flange or rim 7, having an inwardly-extending top 7^a. This rim or flange is slightly higher than the partition 6. Between this longitudinal partition and the sides of the table extend shallow cross-riffles 8, which facilitate the formation of a bed of concentrates or slimes upon the table when the operation is commenced. These partitions divide the table into a number of shallow compartments 9 and limit the agitation of the pulp until the bed or bottom stratum of slimes is formed, after which the slimes accumulate above the riffles, as they are no longer needed. If, however, the riffles are not in use, the slime-saving process is comparatively slow when the apparatus is first put in operation, owing to the difficulty of starting a bed of material or settling the slimes on the smooth bottom of the table. After the thin bed or lower stratum is formed this bed resists the action of the pulp and water and catches the slimes much faster than the smooth bed or table bottom.

At the head of the table on one side of the longitudinal partition 6 a pulp box or compartment 10 is formed by a transverse partition 12. This partition is provided with a number of openings 13, controlled by individual gates or pivoted cut-offs 14, consisting of small plates pivoted to the partition, as shown at 14^a, and located on the side of the partition opposite from the compartment into which the pulp is discharged for treatment. By means of this series of gate-controlled orifices the feed of the pulp to the body of the table may be very accurately and easily regulated. The orifices 13 are formed in the lower part of the partition, and the pivot 14 is located directly above. The upper extremities of these pivoted gates project above the partition, whereby they may be easily manipulated by the operator. The manner of operating these gates is shown in Fig. 5, in which one of them is shown turned or moved to open or uncover its orifice 13.

The gangue or tailings are discharged at

the head of the machine, but on the opposite side of the longitudinal partition from the feed-compartment 10. To this end the rim or flange forming the head end wall of the table is provided with a discharge-opening 15, controlled by a gate 16, mounted on a spindle 12, pivoted or trunnioned in the rim of the table at one end and in the longitudinal partition at the other end. The spindle or shaft 17 is provided with a segmental gear 18, with which meshes a pinion 19, fast on a spindle 20, journaled in the wall or rim of the table at one end and the longitudinal partition 6 at the other end. This construction permits a very fine or close adjustment of the gate 16, whose function is to maintain a vertically-uniform depth of water or pulp above the bed or stratum of slimes accumulating on the table. As this bed accumulates the gate is raised; otherwise the depth of water or pulp above the bed would continuously diminish and the vibration of the table would cause the water or pulp to disturb the bed of slime; but by keeping the depth of water or pulp uniform this undesirable result is avoided, as the agitation is confined to the pulp or water, which thereby protects the accumulated bed of slimes. In other words, the depth of water is such that the force of the vibratory movement of the table is exhausted or spent upon the water or pulp stratum above the bed of slimes on the same principle that disturbance or agitation on the surface of a body of water has very little or no effect upon the bottom or bed below. This table occupies a horizontal plane and is mounted on legs or pins 21, which engage conical sockets 22, formed in the supporting beams or bars 23. The table when in operation is subjected to a vibratory movement through the instrumentality of any suitable mechanism. As shown in the drawings, a shaft 28 is journaled along one side of the table, and eccentrics 29, mounted on the shaft, are connected with the table by means of spring-rods 30, which extend underneath to the center of the table, one extremity of each rod being connected with the strap of the eccentric, while the other extremity is connected with the table by means of a bolt 31. As shown in the drawings, each rod 20 is composed of a flat piece of metal, which yields sufficiently to permit the throw of the eccentrics as the shaft is rotated, the extremities of the said rod being readily secured to the connected parts. The shaft 28 is provided with fast and loose pulleys 32 and 33.

The material to be treated is discharged into the compartment 10 at the head of the table, and the gates 14 are regulated to properly control the discharge through the openings 13 to the body of the table on the feed side of the partition 6. The shallow riffles 8 check the flow of pulp on the table to facilitate the settling of the slimes until a thin slime-bed is

formed on the bottom of the table, after which the riffles are no longer needed and are finally covered by the bed of slimes. The pulp travels along the table on the feed side of the partition 6, passes through the slot 6^a, and travels thence in the opposite direction, and finally impoverished of its mineral values is discharged as tailings or gangue through the discharge-opening 15, the gate 16 being manipulated, as heretofore described, to maintain a suitable and vertically-uniform depth of pulp or water above the bed of slimes. Attention is called to the fact that the gate 16 is not adapted to close or partially close the opening 15, since the said opening is at all times wide open for the discharge of the gangue. The gangue is compelled to flow over this gate before passing through the discharge-opening. Hence by raising the gate the depth of water or pulp maintained on the bed of the table is increased. The result of this operation will be readily understood from the description heretofore given. As the pulp travels from the feed-box 10 in the direction of the arrows shown in Fig. 1 and as just described it is gradually impoverished of its mineral values, the heaviest of these values settling first and the others in the order of their gravity, the lightest or finest being the last to settle. The path over which the pulp must travel on the table is supposed to be of sufficient length to save practically all of the values.

Having thus described my invention, what I claim is—

1. A horizontally-arranged slime-saving table having a vibratory movement transverse to the travel of the pulp thereon, said table being provided with a feed-compartment having gate-controlled openings for admitting the pulp to the body of the table, and a discharge-opening for the gangue or tailings, the discharge-opening being remote from the feed box or compartment, the table being also provided with a gate pivotally mounted near the discharge-opening, normally occupying a horizontal position below said opening and capable of adjustment on its hinge or pivot to maintain a suitable predetermined depth of water or pulp above the slime-bed as it accumulates on the table, substantially as described.

2. A horizontally-arranged slime-saving table having a vibratory movement transverse to the direction of the pulp's travel thereon, and provided with a feed-box from which the pulp passes to the body of the table which is provided with a discharge-opening remote from the feed-box, and a gate pivotally mounted near said opening, normally occupying a horizontal position below the discharge-opening and capable of inclined adjustment between the horizontal and vertical whereby a vertically-uniform predetermined depth of water or pulp is maintained above the accumulating bed or stratum of slimes on the bottom of the table.

3. The combination of a horizontally-arranged slime-saving table provided with a feed-box and having a discharge-opening remote from the said box, the table being provided near the discharge-opening with a gate 5 located adjacent and in front of said opening, a spindle journaled in the table and upon which the gate is mounted, the gate normally occupying a horizontal position below the discharge-opening and projecting toward said opening, a segmental gear fast on the spindle, a pinion meshing with said gear, and a spindle upon which the pinion is made fast, the said spindle being journaled in the table and arranged to be operated to control the gate, whereby the latter is capable of inclined adjustment in front of the discharge-opening, substantially as described.

4. A horizontally-arranged slime-saving table comprising a feed-box separated from the body of the table by a partition provided with a series of orifices, gates pivoted on the said partition for controlling the said orifices, shallow cross-ruffles located on the bottom of the table, to facilitate the initial settling of the slimes as described, the table having a discharge-opening remote from the feed-box, and a pivoted gate located adjacent the discharge-opening for the purpose of maintaining a predetermined depth of water or pulp above the accumulating bed or stratum of slimes on the bottom of the table, the said gate normally

occupying a horizontal position below and in front of the discharge-opening of the table and projecting toward said opening, substantially as described.

5. The combination of a horizontally-arranged slime-saving table, means for imparting a vibratory movement to the table transverse to the travel of the material thereon, a longitudinal partition dividing the table into longitudinal compartments, said partitions having a slot adjacent the tail of the table, shallow transverse ruffles located at intervals in both longitudinal compartments, a gated feed-box from which the pulp passes to one compartment of the body of the table, the table having a discharge-opening in the other compartment adjacent the feed-box, and an adjustable gate mounted near the discharge-opening and normally occupying a horizontal position below the discharge-opening and arranged to be elevated to cause the pulp to flow over it before reaching the discharge-opening, the said gate being for the purpose of maintaining a predetermined, uniform depth of water or pulp above the bed or stratum of slimes on the table.

In testimony whereof I affix my signature in presence of two witnesses.

JACOB J. SMITH.
